UNITED STATES PATENT OFFICE.

WILLIAM J. MORGAN, OF ST. LOUIS, MISSOURI, ASSIGNOR, BY MESNE ASSIGNMENTS,
TO CHARLES B. MERRELL, OF CHICAGO, ILLINOIS.

INCLOSED FUSE.

1,117,590.

Specification of Letters Patent.

Patented Nov. 17, 1914.

Application filed August 20, 1913. Serial No. 785,728.

To all whom it may concern:

Be it known that I, WILLIAM J. MORGAN, a citizen of the United States, residing at the city of St. Louis, State of Missouri, have invented certain new and useful Improvements in Inclosed Fuses, of which the following is a specification, reference being had to the accompanying drawings, forming a part hereof, in which—

Figure 1 is a perspective view of an inclosed fuse embodying my invention in preferred form, one of the end-caps or casing closures being partly broken away; Fig. 2 is a longitudinal sectional view through the same; Fig. 3 is a longitudinal sectional view thereof at right angles to that shown in Fig. 2; Fig. 4 is an end view of the same; Fig. 5 is a cross-sectional view on the line 5—5, Fig. 2; Fig. 6 is a cross-sectional view of the fuse as when in course of assemblage of the parts thereof, showing the casing transversely distorted or elongated to receive the contact-blades and their connecting or attached fusible element or link; Fig. 7 is a plan view, with the casing partly broken away and in longitudinal section, of an inclosed fuse embodying my invention, showing a slightly modified form of attaching or fastening the fusible element or link to the contact-blades and also of fastening the end-caps operatively upon the fuse-casing; Fig. 8 is a fragmentary longitudinal sectional view of a slightly modified form of fuse embodying my invention; Fig. 9 is an end view of the form of fuse shown in Fig. 8.

This invention relates generally to electric safety fuses and more particularly to certain new and useful improvements in that class of electric safety fuses commonly known as inclosed or cartridge fuses. Fuses of this class usually comprise a hollow shell or casing of fibrous or analogous material, end-caps or closures, terminal members or contact-blades extending longitudinally of the casing and projecting therefrom at its ends through the end-caps, a suitable fusible element or link suitably electrically connected to the contact-blades and bridging the space therebetween within the casing, the fusible element having a current-carrying capacity less than the current-carrying capacity of the contact-blades and being adapted to carry the current up to a certain rated amperage and to blow or fuse on an overload or increase of current, thereby protecting

the electric circuit in which the fuse may be arranged or inserted, as will be well understood, and a filling of suitable non-conducting material, preferably in a finely divided state, the function of which is to dissipate the heat and provide minute paths or interstices for the escape of the vapor or gas evolved upon the fusing or blowing of the fusible element. Heretofore, so far as I am aware, the blade-terminals and end-caps or closures of the casing have been usually secured within and upon the casing by means of fastening screws or other analogous members; but fuses so constructed are more or less difficult of assemblage and more or less expensive to manufacture.

The objects of my present invention are to provide a fuse of the class stated wherein the terminal or contact-blades are rigidly operatively fixed within the fuse-casing without the use of any separable fastening means or members; to provide a fuse of the kind stated having the end-caps or casing-closures securely held operatively upon the casing by fastening means or members having no engagement with the fuse-casing and engaging only with the terminal or contact-blades; to provide a fuse of the kind stated of few, readily assembled parts and of simple construction and which may be cheaply and economically manufactured and marketed; and to improve generally upon and simplify the construction of fuses of the class mentioned.

With these and other objects in view, my invention resides in certain novel features of construction, arrangement, and combination of parts, all as will hereinafter be described and afterward pointed out in the claims.

In the accompanying drawings, in which like reference characters refer to like parts throughout the several views, and referring now more particularly to Figs. 1 to 7, inclusive, 1 indicates the fuse-casing, which is preferably an open-ended tubular shell of fibrous or analogous material and which may be of any suitable length and diameter as required according to the desired size or current-carrying capacity of the fuse. 2—2 indicate suitable flanged or cup-shaped preferably metallic caps which are adapted, in the finished fuse, to fit on casing 1 at its opposite ends and provide closures therefor, 3 indicates the fusible element or link, which is preferably in the form of a single flat

strip of suitable material. Link 3 extends lengthwise of, and preferably centrally within, casing 1 and at its opposite ends is electrically connected as by screws 4 (see Figs. 2 and 3), or by solder, as at 5 (see Fig. 7), or by other suitable means, to the preferably reduced inner ends or portions 6^a—6^a of oppositely-disposed relatively thick, heavy, preferably flat and stamped or otherwise cut blades 6—6 of copper or other suitable conducting material. These blades 6—6, as shown, also extend lengthwise of casing 1 and at their main or body portions 6^b—6^b, which preferably have a width slightly less than the inner diameter of casing 1, project outwardly, in the finished fuse, through suitable elongated or rectangular slots in the face of end-caps 2—2 and thereby form contact terminals for the fuse, being readily engaged with knife-blade contacts or the like. At a suitable point lengthwise between their ends, preferably at the base of its reduced inner portion 6^a, each of said blades 6 is integrally provided with a pair of oppositely-disposed laterally-projecting rigid lugs or fingers 6^c preferably rectangular in cross-section which are adapted in the finished fuse, to fit in suitable diametrically opposite openings or perforations 1^a provided in casing 1 adjacent the ends thereof, blades 6—6 at said lugs or fingers 6^c having each a width approximately equal to, or the same as, the outer diameter of casing 1 and said openings 1^a having a size or area, as shown, just sufficient to accommodate said fingers 6^c. Surrounding fusible element or link 3 and filling the interior of casing 1, is a filling 7 of any suitable non-conducting material, preferably in a finely divided state, such as slaked lime, adapted to dissipate the heat and provide minute paths or interstices for the escape of the vapor or gas arising or evolved upon the fusing or blowing of link 3, and to hold caps 2—2 firmly upon casing 1 and prevent their being blown off casing 1 by the expansion of the gases generated on the fusing of link 3, I preferably, as shown particularly in Figs. 1 and 2, pass cotter-pins or the like 8—8 transversely through blades 6—6 at a point just outside the end face of caps 2—2, or employ solder or the like 9, as shown in Fig. 7, for such purpose, end-caps 2—2 being provided, as is usual, with suitable vent-perforations or openings 10—10 and the flanges thereof being preferably of a length inwardly to overlie and cover said casing-openings 1^a and the exposed ends of blade-lugs or fingers 6^c.

In assembling the parts of my new fuse, casing 1, which is somewhat resilient or elastic due to the nature of its fibrous or analogous composition and may hence be properly described as a resilient casing, is first transversely distorted, as by means of 65 a vise or other tool or instrument, to ellip-

tically elongate the same to accommodate blades 6—6 and their fingers 6^c, the major axis of casing 1, when so elliptically elongated, being slightly greater than the width of blades 6—6 at their said fingers 6^c, as shown particularly in Fig. 6. Blades 6—6 and their attached or connected fusible element or link 3 are then lengthwise inserted into the so elliptically elongated casing 1 until said pairs of fingers 6^c thereof register with said casing-openings 1^a, whereupon, on casing 1 being released from said vise or other instrument or tool and again, through its own elasticity or resiliency, assuming its original or former cylindrical shape, fingers or lugs 6^c enter said openings 1^a, and I have found that, by means of the engagement as described of blades 6—6 through their said fingers or lugs 6^c with casing 1, casing 1 and blades 6—6 and their attached or connected fusible element or link 3 are rigidly, firmly, tightly, and positively held operatively together, the use of other or additional fastening members or means for such purpose being entirely obviated. Filling 7 and end-caps 2—2 are now, as described, operatively placed within and upon casing 1, when the fuse is ready for marketing. Cotter-pins or the like 8, or solder 9, extending across or over a considerable area of the outer face of end-caps 2—2, enable end-caps 2—2 to withstand, and prevent end-caps 2—2 being blown off casing 1 by, the expansion or explosive effect of the gases generated within casing 1 on the fusing of element or link 3.

In Fig. 8, I have shown a slightly modified form of my new fuse which is more particularly adapted for engagement with spring-clips or analogous circuit terminals. Accordingly, the outer portions 11^b—11^b of the blades 11—11 of the fuse shown in Fig. 8, and which outer portions 11^b have preferably the same width as inner blade-portions 11^a, terminate substantially flush with the outer face of end-caps 2—2, end-caps 2—2 being electrically connected with blades 11—11 and held operatively upon casing 1 against the expansive force of the gases generated on the fusing of link 3 as by means of solder or the like 12 spread, as shown, upon the outer faces thereof and over the exposed ends of blades 11—11. Otherwise this form of my new fuse is substantially similar in all respects to the preferred form of my new fuse shown in Figs. 1 to 3, inclusive, blades 11—11 similarly rigidly engaging with casing 1 by means of laterally-projecting oppositely-disposed integral fingers or lugs 11^c, as shown.

My new fuse, as will be evident from the foregoing, is exceedingly simple in construction, comprises few parts and the parts of which may be easily and quickly operatively assembled, and may be economically and 125

cheaply manufactured, and it will be seen that by my new fuse I provide a firm and rigid connection between the blades, end-caps, and casing without the use of, or necessity for, any fastening or attaching means, such as screws and the like, which have heretofore, so far as I am aware, been generally employed for such purpose. And it is to be understood that changes in the construction, arrangement, and combination of the several parts of my new fuse may be made and substituted for those herein shown and described without departing from the nature and principle of my invention.

Having thus described my invention, what I claim and desire to secure by Letters Patent is:

1. In a fuse of the class described, a resilient casing provided with diametrically opposite openings, and a fuse-link terminal having oppositely-disposed rigid securing portions projecting into said openings and thereby engaging with said casing; substantially as described.

2. In a fuse of the class stated, a resilient tubular casing provided with diametrically opposite openings, and a fuse-link terminal having oppositely-disposed rigid securing portions projecting into said openings and thereby engaging with said casing, said openings having an area approximately the same as that of the cross-section of said securing-portions; substantially as described.

3. In a fuse of the class stated, a resilient tubular casing provided with diametrically opposite openings, and a fuse-link terminal extending lengthwise of and within said casing and having oppositely-disposed laterally-extending rigid securing-portions substantially rectangular in cross-section projecting into said openings and thereby rigidly engaging with said casing, said openings having an area approximately the same as that of the cross-section of said securing-portions; substantially as described.

4. In a fuse of the class stated, a resilient tubular casing provided with diametrically opposite openings, and a fuse-link blade-terminal extending lengthwise of and within said casing and having oppositely-disposed laterally-projecting integral securing-lugs substantially rectangular in cross-section fitting in said openings and thereby rigidly engaging directly with said casing, the width of said blade-terminal at said lugs being approximately the same as the outer diameter of said casing and said openings having an area approximately the same as that of the cross-section of said securing-portions; substantially as described.

5. In a fuse of the class stated, a resilient tubular casing provided with diametrically opposite openings, a slotted end cap fitting on and providing a closure for an end of said casing, a fusible element within said casing, and a blade-terminal having oppositely-disposed rigid lateral extensions projecting into said openings and thereby engaging with said casing, said blade-terminal having electrical connection with said fusible element and having a portion fitting in the slot of said end-cap; substantially as described.

6. In a fuse of the class stated, a resilient tubular casing provided with diametrically opposite openings, a slotted end-cap fitting on and providing a closure for an end of said casing, a fusible element within said casing, a blade-terminal having oppositely-disposed rigid lateral extensions projecting into said openings and thereby engaging with said casing, said blade-terminal having electrical connection with said fusible element and having a portion fitting in the slot of said end-cap, and means engaging with said blade-terminal beyond the end of said casing for securing said end-cap in operative position upon said casing; substantially as described.

7. In a fuse of the class stated, a resilient tubular casing provided with diametrically opposite openings, a slotted end-cap fitting on and providing a closure for an end of said casing, a fusible element within said casing, a blade-terminal having oppositely-disposed rigid lateral extensions projecting into said openings and thereby engaging with said casing, said blade-terminal having electrical connection with said fusible element and having a portion projecting through the slot of said end-cap and providing a circuit-contact member for the fuse, and means engaging with said blade-terminal beyond the end of said casing for securing said end-cap in operative position upon said casing; substantially as described.

8. A blade-terminal of conducting material for a fuse of the class described, the same comprising a body-portion and oppositely-disposed casing-securing lugs projecting laterally from, and lying in the plane of, said body-portion; substantially as described.

In testimony whereof, I have signed my name to this specification in the presence of two subscribing witnesses.

WILLIAM J. MORGAN.
